O. W. VALLIER

SWING SPOUT FOR SINK FAUCETS

Filed March 2, 1925

By Harry D. Wallace

Attorney.

UNITED STATES PATENT OFFICE.

ORVIS W. VALLIER, OF WATERTOWN, NEW YORK, ASSIGNOR TO J. B. WISE INCORPORATED, OF WATERTOWN, NEW YORK, A CORPORATION OF NEW YORK.

SWING SPOUT FOR SINK FAUCETS.

Application filed March 2, 1925. Serial No. 12,766.

To all whom it may concern:

Be it known that I, ORVIS W. VALLIER, a citizen of the United States, residing at Watertown, in the county of Jefferson and State of New York, have invented certain new and useful Improvements in Swing Spouts for Sink Faucets, of which the following is a specification.

This invention relates to sink and other faucets, and has particular reference to faucets wherein the discharge spout is arranged to be swung about the axis of the faucet, for delivering water at different temperatures to different parts of the sink.

The object of the invention is to provide novel water dispensing mechanism, wherein a jointed spout, comprising two or more sections which are pivoted to the body of the dispensing valve, and are adapted to be swung as one part, or independently, in different directions relatively to the valve body. A further object is to provide novel means for effecting the swivel or pivot joint between the spout and the valve body, as well as between the sections of the spout. A further object is to provide novel and simple means for adjusting certain of the swivelling members, for taking up slack and wear, as well as for effectively sealing the said joints against leakage, without the use of any of the ordinary short life rubber or other compressible packings. And a further object is to generally improve and simplify the construction and arrangement of sink faucets and other water dispensing fittings.

The various features of the parts of the invention will be understood from the detailed description which follows, and by reference to the accompanying drawing, in which—

Figure 1 is an elevational view of an ordinary kitchen sink, to which my improvement is applied; showing by full and dotted lines the swingable nature of the jointed spout of the faucet. Fig. 2 is a partial front side elevation, and partial central vertical section; showing the construction and arrangement of the adjustable water-tight joints. Fig. 3 is respectively an enlarged end and a side view of one of the adjusting collars. And Fig. 4 is respectively a top plan and a side elevation of the collar and complementary sleeve, in connection with the water receiving arm of the spout.

In the drawing, 2 represents the upright portion of the sink, and has perforation 2' and 2^a through which the cold and hot water supply pipes are brought from an adjacent wall (not shown) to the forward side of the sink, and 2^c represents the tray of the sink. 3 represents a single mixing-valve or cock, by which the cold and hot water are dispensed, and comprises an upright hollow body 3', the latter having an open-top cylindrical portion 3^a, which is closed and sealed by a cap 3^b, and a depending threaded neck 3^c, for the discharge of the water. 4 and 4' represent respectively integral cold and hot water arms, which receive the water from supply pipes 4^a and 4^b, and discharge the water through alining ports 4^c—4^d, into a common valve chamber 3^d of the body, as best seen in Fig. 2. The drawing and the discharge of the water is controlled by a valve 6, which is rotatable in the chamber 3^d, and is operable by means of a stem 6', which extends upwardly through the body and cap 3^b, and its upper end is fitted with a handle 6^a, by which the valve is rotated. The valve 6 is formed with a concentric mixing-chamber 6^b, and with radial ports 6^c—6^d that communicate with said chamber, the said ports being arranged to register respectively with the ports 4^c—4^d, as shown in Fig. 2. The swinging of the handle 6^a in opposite directions effects the dispensing of cold, warm or hot water, in a well-known manner.

The water passes from the ports 4^c—4^d into the chamber 6^b of the valve, and thence gravitates through the open bottom of said chamber towards the neck 3^c, from which the water is carried away and discharged at different parts of the sink, or beyond the sink, by means of a single conductor, which in the present showing comprises a number of jointed sections as 7 and 8 (see Figs. 1 and 2). The section 7 of the spout comprises a horizontally disposed tubular body 7', whose opposite ends are formed with hollow spherical portions 7^a—7^b. The part 7^a is provided with an elongated upwardly extending tubular neck 7^c, which is arranged to be inserted upwardly into the smallest bore of the neck 3^c of the body, as shown in Fig. 2. Near its top end the neck 7^c is externally threaded for receiving an adjusting collar or nut 9, and below the said collar, the neck 7^c is fitted with a plain sleeve 9',

which is slidable on the neck. Screwing the nut 9 in opposite directions regulates the extent to which the free end of the neck 7^c may be inserted in the bore of the body 3 below and concentric to the valve 6. The arm 7 of the spout is pivotally and detachably held in place, by a gland-nut 10, which telescopes the neck 7^c below the sleeve 9', and engages the threads of the neck 3^c of the body. The sleeve 9' is employed for suitably spacing the relatively deep nut 10 from the collar 9, and also serves as a washer for preventing the tightening of the gland-nut from disturbing the adjustment of the collar 9 and related parts. Between the free end of the neck 3^c and the inner face of the nut 10 may be disposed a ring of any suitable compressible packing, as 10', the said packing preferably surrounding the lower end of the sleeve 9', as shown. The neck 3^c of the valve body is counter-bored, as at 3^e, to receive the adjusting ring 9 and the sleeve 9', as shown in Fig. 2, the said parts preferably fitting closely for preventing leakage, and yet allowing the swelling of the spout. By this construction and arrangement of the swivel mechanism, the tortuous nature of the joint between the arm 7 and the valve body effectively prevents leakage, and the valve body and arm may be adjusted relatively to each other, by means of the ring 9. The opposite end of the member 7 is provided with an integral downwardly extending externally threaded neck 7^d, which is preferably bored out like the neck 3^c, to pivotally receive a tubular neck 8', which extends upwardly from a similar spherical portion 8^a, of the section 8. The neck 8' is externally threaded near its free end for adjustably receiving a threaded collar 9, and below the said threads a similar sleeve 9' is applied to the neck. The section 8 is preferably disposed parallel to section 7 and may also be held pivotally in place, by means of a gland-nut 10^a the said joint 45 being provided with a packing 10'. In the preferred arrangement, the packings 10' comprise an oily or greasy substance, which tends to lubricate the joints between the gland-nuts, the sleeves and the necks 3^c— 50 8', as well as to render the said joints watertight. Owing to the relatively close fitting of the swivel parts, the packings rarely require renewing. The free end of spout-member 8, is preferably formed with a 55 downwardly bent nozzle 8^b, for directing the discharge of the water towards the bottom of the tray 2^c. The reach of the arms 7—8 when extended may be such that the water may be discharged beyond the tray of the 60 sink, as shown in Fig. 1. By the provision of two or more arms, as 7—8, the water may be supplied to all parts of the tray 2^c, or may be discharged into a number of vessels located in or adjacent the sink. 65

Having thus described my invention, what I claim, is—

In a combination with a swing spout, a chambered casing having a depending externally threaded and counterbored neck, 70 an upwardly extending neck on the spout engaged with the bottom of the chamber above the counterbored part of the neck of the casing, a collar surrounding the upper end of the spout neck and threaded 75 thereon, the counterbored part of the casing neck forming a shoulder, against which latter said collar abuts, a sleeve surrounding the spout neck and abutting the collar, packing engaged with the bottom end of the 80 casing neck and a gland nut threaded over the casing neck and engaged with the packing and with the outer end of the sleeve.

In testimony whereof I affix my signature.

ORVIS W. VALLIER.
